UNITED STATES PATENT OFFICE.

DONALD S. BARROWS, OF ROCHESTER, NEW YORK.

CAR-UNDERFRAME.

1,358,501.

Specification of Letters Patent.

Patented Nov. 9, 1920.

Application filed May 31, 1918. Serial No. 237,486.

To all whom it may concern:

Be it known that I, DONALD S. BARROWS, a citizen of the United States, residing at Rochester, in the county of Monroe and 5 State of New York, have invented certain new and useful Improvements in Car-Underframes; and I do hereby declare the following to be a full, clear, and exact description of the invention, such as will enable others skilled in the art to which it 10 appertains to make and use the same.

The invention relates to car underframes, and more particularly to means connected to the wooden center sill for replacing the old 15 wooden draft sills or timbers, the said means being adapted to strengthen the wooden underframe and to afford a strong, efficient and reliable support, container or housing for the draft rigging parts.

20 The principal object of my invention, generally stated, is to provide a draft arm in which the load transmitted to the lower portion thereof by the draft rigging is carried to the car center sill at a point where the sill 25 is strengthened and reinforced, the load transmitting portion of the draft arm being so constructed and arranged as to prevent the danger of buckling of this portion of the draft arm. To this end the main feature of 30 my invention broadly considered consists in providing a metallic draft arm connected to the upright face of the center sill and extending under the end sill and over and to the rear of the body bolster, a portion of the 35 draft arm between the end sill and bolster depending below the lower face of the center sill to provide a housing or container in conjunction with a corresponding part of the adjacent draft arm, for the draft rigging 40 parts, and means for reinforcing the lower edge of the said draft arms, said means extending from over the bolster to a point on the said depending portion.

There are other features of the invention 45 as will appear from the more detailed description of the same when taken in connection with the accompanying drawings, in which:

Figure 1 is a longitudinal central vertical 50 section of a car underframe showing the invention applied thereto, some of the draft rigging parts being shown in side elevation for the sake of clearness.

Fig. 2 is a view partially in plan and par-

tially in horizontal longitudinal section on 55 line 2—2 of Fig. 1.

Fig. 3 is a side elevation of the draft arm.

Fig. 4 is a section taken on line 4—4 of Fig. 2.

Fig. 5 is a section taken on the line 5—5 60 of Fig. 2, and

Fig. 6 is a section taken on the line 6—6 of Fig. 1.

Throughout the specification and drawings like parts are designated by like reference characters.

The numerals 1, 1 designate the center sills of a car underframe, 2 the end sill, 3 the striking block, and 4 the striking casting which is connected to the outer face of 70 the block 3, and 5^a a tie member connecting the lower faces of the center sills 1 adjacent the body bolster 5. To the inner or adjacent faces of the center sills 1 are connected, preferably by means of the bolts 6, the draft 75 arms 7. Each draft arm 7 comprises a plate-like member which is adapted to overlie the adjacent face of the center sill 1 and which extends along the upright face of the said sill from end sill to and in rear of the 80 body bolster. Intermediate the end sill and bolster the draft arm is provided with a depending portion 7^a, which portion is preferably offset from the vertical plane of the upper portion of the draft arm, as shown at 9 85 and 10. In old wooden car construction the spacing of the center sills was materially less than the requirement of the Master Car Builders' Association for steel underframes, 90 which requirement is twelve and seven-eighths inches from inside face to inside face of the draft arm or center sills of a steel underframe car, and by offsetting the draft arms as described above, the vertical faces of the depending portions of the draft arms 95 are spaced to agree with the requirements of the Master Car Builders' Association. These depending portions of the draft arms afford a draft rigging housing or container suitable for the reception of the modern type 100 of draft rigging.

For convenience, the invention has been illustrated in connection with a well known type of draft rigging which comprises a drawbar 11, a front follower 12, a rear follower 13, springs 14 interposed between the front and rear followers, the drawbar and followers being operatively connected by

means of the horizontally disposed connecting means or links 15. Passing through the drawbar, the front follower and the rear follower, respectively, are the transversely disposed keys 16, 17 and 18. These keys, as is well understood and as will be clearly seen from the disclosure of Fig. 2, pass through slots in the links 15 and through elongated slots 19, 20 and 21 in the depending portions of the draft arms 7, the front key 16 being located midway of its receiving slot. The key 17 normally occupies a position in the forward end of the draft arm slot, and the key 18 normally occupying a position at the rear of the draft arm slot, so that on forward movement of the drawbar the front key 16 will be moved outwardly and carry with it the links 15, the rear key 18 and the rear follower 13, the front follower 12 being held stationary by the key 17.

To the outer faces of the depending portions of the draft arms are connected the cheek-plates 22. Each of these plates is provided with a plurality of slots to correspond with the before-mentioned slots in the draft arms, and each may be provided with inwardly extending bosses adapted to line the walls of the slots in the draft arms to prevent the upsetting of these walls by the action of the keys. It is to be understood that I do not limit myself to the application of the cheek-plates to the outer faces of the draft arms, and that the showing of the drawing in this respect is merely for convenience.

To strengthen the depending portion 7^a of the draft arms 7 there is preferably provided on the outer face of each draft arm adjacent the lower face of the center sill an angle bar reinforcing means 23, one flange, 24, of which is adapted to contact and be secured to the outer face of the draft arm and the other flange, 25, being adapted to abut and be secured to the center sill. In the form of draft rigging illustrated, the flange 24 is interposed between the cheek-plate and the adjacent draft arm, and the securing means are adapted to pass through the cheek-plates 22, the flanges 24 and the draft arms 7. To counteract the bending tendency of the upper portion of the draft arms, each draft arm is provided adjacent its upper edge with reinforcing means 26 which may be and preferably is in the form of an angle bar 27. This angle bar preferably overlies and extends on opposite sides of the body bolster 5, and as the angle bar is firmly riveted to the adjacent face of the associated draft arm it may be considered for all purposes as a part thereof, and it therefore changes the draft arm at this point from a flat plate to an angle bar having a long vertical or upright flange and a

With draft arms of the old type great difficulty has been experienced owing to the liability of the draft arm buckling between the rear follower and the bolster, due to heavy buffing stresses. In my device I obviate this danger by providing a reinforcing means 28 which extends along the lower edge of each draft arm from a point in front of the rear follower 13 to a point in rear of the bolster 5. This reinforcing means may be and preferably is in the form of an angle bar. To prevent the interference of the reinforcing means 28 with the moving parts of the draft rigging, I preferably construct the reinforcing means in a plurality of parts 29 and 30, the portion 29 comprising an angle bar which is connected to the outer face of the depending portion 7^a of each draft arm adjacent the lower edge thereof, the said angle bar 29 extending rearwardly along the lower edge of the depending portion to a point in rear of the rear follower 13 and may and preferably does extend along the inclined portion 7^b of the draft arm to a point in alignment with the lower portion of the center sills. The portion 30 of the reinforcing means 28 is also preferably formed as an angle bar and is connected to the inner face of each draft arm so as to avoid interference with the center sills. This angle bar 30 is connected to the lower edge of the rearwardly extending portion of the draft arms 7, and preferably extends forwardly of the bolster 5 to and along the inclined portion 7^b of each draft arm so as to overlap the upwardly extending portion of the adjacent angle bar 29. The adjacent ends of each pair of angle bars 29 and 30 are connected to the intervening portion of the draft arm by means of the rivets 31. By this construction the inclined portions 7^b of the draft arms are greatly strengthened and reinforced against all possible danger of buckling; the angle bars riveted to the opposite sides of the draft plate forming with each draft plate a built-up beam of substantially T-section. This construction also transmits the buffing loads to the car center sills at points where the latter are best able to withstand these excessive strains.

Having now fully described my invention, although it is to be understood that the terms employed are to be taken in their descriptive and not in their limiting sense, what I claim is:

1. In a car underframe, the combination with wooden center sills, of metallic draft plates connected thereto, each of which is provided with a depending portion said portions extending below the lower faces of the said sills and below the lower edges of the rearwardly extending portions of the draft plates, said depending portions being outwardly flared to provide a draft rigging

housing and means for reinforcing the lower edges of the said plates, said means comprising angle bars connected to the said portions of the plates and extending from 5 end to end thereof.

2. In a car underframe, the combination with wooden center sills, end sill and bolster, of metallic draft plates connected to the upright faces of the said sills, said 10 plates being substantially equal in width to the said center sills between the said bolsters and each being provided with a depending portion intermediate the bolster and end sill the inner ends of the said 15 depending portions sloping upwardly adjacent the said bolsters, and means for reinforcing the lower edges of the said plates adjacent the said bolsters, said means comprising angle bars each connected to the inner face of one of the said plates adjacent 20 the bolster and extending forwardly thereof, and an angle bar connected to the outer face of each plate adjacent the depending portion thereof, the adjacent ends of each 25 pair of angle bars being adapted to extend in the same direction and to overlap.

3. In a car underframe the combination

with the center sills, end sill and bolster, of a pair of metallic draft plates connected to the upright faces of the said sills and extending under the end sill and over and to the rear of the said bolster, means for reinforcing said plates between the end sill and bolster and means for reinforcing said plates adjacent the said bolster, said first 30 named means including a pair of angle bars connected to the outer face of each of the said plates and extending rearwardly from the end sill toward the said bolster one angle bar of each pair being connected to 35 the adjacent center sill, said last named means including a member connected to the inner face of each plate adjacent the said bolster, said members being adapted to coincide with the lower edge of the adjacent 40 plate, the said members extending forwardly of the bolster and each being adapted to overlap and be connected to the adjacent end of one of the first named angle 45 bars, said overlapping ends extending in 50 the same direction.

In testimony whereof I affix my signature.

DONALD S. BARROWS.
